A. ROSS

Des. 161,538

DISPLAY STAND

Filed March 13, 1950

ALEXANDER ROSS,
INVENTOR,

BY Neil M. Elford
ATTORNEY

UNITED STATES PATENT OFFICE

161,538

DISPLAY STAND

Alexander Ross, New York, N. Y.

Application March 13, 1950, Serial No. 8,505

Term of patent 14 years

(Cl. D80—9)

To all whom it may concern:

Be it known that I, Alexander Ross, a citizen of the United States of America, residing in New York city, county of New York, and State of New York, have invented a new, original, and ornamental Design for a Display Stand, of which the following is a specification, reference being had to the accompanying drawing, forming part thereof, wherein,

The figure is a perspective view of a display stand, showing my new design.

I claim:

The ornamental design for a display stand, substantially as shown.

ALEXANDER ROSS.
